FISHING NET YOKE

James D. Maxwell, 11001 SE. 19th,
Vancouver, Wash. 98664

Filed Apr. 12, 1971, Ser. No. 133,458

Term of patent 14 years

Int. Cl. D22—05

U.S. Cl. D22—22

Fig. 1

Fig. 2

Fig. 3

Fig. 4

FIG. 1 is a top plan view of a fishing net yoke embodying my new design, the top and bottom surfaces of the yoke being symmetrical in design;

FIG. 2 is an end view taken from the left side of FIG. 1;

FIG. 3 is an end view taken from the right side of FIG. 1; and

FIG. 4 is an enlarged fragmentary sectional view taken on the line 4—4 of FIG. 1.

I claim:

The ornamental design for a fishing net yoke, as shown and described.
